WINDOW FRAMES

Joseph Sylvan, Berkley, Mich.

Application June 17, 1952, Serial No. 293,886

8 Claims. (Cl. 189—75)

This invention relates to a window frame structure and particularly to improvements in the jamb assembly thereof.

The invention is embodied in a window assembly of the storm sash screen type wherein three guide channels are provided adapted to carry three slideable sash. Two of these sash may be storm sash and the third sash a screen sash. The invention is here shown as embodied in such an assembly formed of metal such as aluminum.

An object is to provide such a window structure wherein the window sash may be readily removed from the inside of a building for washing and easily and quickly replaced in position.

A meritorious feature is the provision of a jamb assembly so constructed that the removal and replacement of sash is facilitated by partially disassembling the jamb structure and this can be readily and quickly accomplished.

Another meritorious feature is the provision of a jamb assembly of the character specified wherein the lower portion of certain guide channel members may be detached from the remainder of the jamb assembly so as to facilitate the removal of sash therefrom.

A further meritorious feature is the provision of a jamb assembly of the character described wherein two of the guide channels are embodied in parts which are so associated with the remainder of the assembly as to define with such remainder three guide channels but the parts which make up the two guide channels may be removed from the remainder of the assembly so far as the lower portion of the assembly is concerned while remaining a part thereof through the upper portion of the assembly.

Another object is the provision of a jamb assembly in a window structure of the character specified wherein one of the guide channel walls is bent at the upper corner of the lower portion of such guide channel out of the plane of the channel and into the plane of the adjacent channel forming a yielding part which is adapted to engage underneath a sash when elevated thereabove to support the same.

Other objects, advantages and meritorious features will appear from the following description, claims and accompanying drawings, wherein:

Fig. 1 is an outside elevation of a window structure embodying the invention;

Fig. 2 is a vertical sectional view taken on the line 2—2 of Fig. 1;

Fig. 3 is a horizontal fragmentary sectional view taken on the line 3—3 of Fig. 1;

Fig. 4 is a horizontal fragmentary sectional view taken on the line 4—4 of Fig. 1;

Fig. 5 is a vertical fragmentary sectional view taken on the line 5—5 of Fig. 1 but showing all three sash elevated;

Fig. 6 is a perspective of that portion of the fragment of the jamb assembly shown in Fig. 5;

Fig. 7 is a perspective of a portion of the jamb assembly

2

showing the removal of the lower portion of the guide channel of the subassembly;

Fig. 8 is a horizontal sectional view taken on the line 8—8 of Fig. 1;

Fig. 9 is a horizontal sectional view taken on the same line as Fig. 8 but showing the lower portions of two of the guide channels withdrawn from the remaining portion of the assembly;

Fig. 10 is a horizontal sectional view taken on the line 10—10 of Fig. 1.

The window structure is shown as mounted within a window opening on the outside thereof. Such window opening is provided in a building that is ordinarily constructed with a stationary jamb element 20 which is rabbed as at 22 providing a shoulder upon which the assembly may be secured by means of screws, nails or the like 24, as shown particularly in Figs. 3, 4, 6 and 7. The window opening of course is provided with a header and a sill shown in dotted outline in Fig. 1.

My window structure comprises a pair of opposed complementary jamb assemblies each exhibiting three guide channels. These jamb assemblies are secured together at the top by a header 26 which may be formed of sheet metal shaped so as to define three header wells 25 within which the upper rails of the three sash carried by the window structure may be received. The two jamb assemblies are connected together at the bottom by a sill assembly 28, shown more particularly in Fig. 2 which exhibits an upstanding portion 30 terminating in a flange 32 adapted to seat upon the stationary window sill. The portion 30 is provided with an upstanding ledge 34 on the inside of the window opening. The invention claimed resides particularly in the construction of the jamb assemblies. The two jamb assemblies are similar.

Each jamb assembly comprises a base channel member 36 which is directly secured by the screws 24 to the stationary jamb on the window. This base channel member extends through the length of the jamb assembly. Connected with and seating upon the base channel member 36, as shown particularly in Figs. 3 and 4, is a Z-shaped member 38. This member is generally Z-shaped. It has a leg 40 which is folded over upon itself and forms a lip receiving channel. This leg 40 is received within the base channel, as shown particularly in Figs. 3, 4 and 6. The screws 24 extend through the leg 40 of the Z-shaped member and secure the same within the base channel, as shown particularly in Figs. 3 and 4. The other leg of the Z-shaped member which is indicated as 42 and which projects in the opposite direction from the leg 40 constitutes a side wall of one of the three guide channels. 50 This leg 42 may be folded over upon itself as at 43 as shown in Fig. 4.

There is a guide channel sub-assembly which is made up of two guide channel members. One guide channel member is indicated by the numeral 44. It is twice the width of a guide channel runway. It is seated upon the base of the Z-shaped member 38. It has one side wall 46 which is spaced such a distance from the side wall 42 of the Z-shaped member that it defines therewith one of the three guide channels. The other guide channel member which goes to make up the guide channel sub-assembly is indicated by the numeral 48. It is seated within the guide channel 44 as shown particularly in Figs. 3 and 4. It has a guide channel wall 50 which is so spaced from the guide channel wall 46 that it defines therewith a guide channel. It has another guide channel wall 52 which with the wall 50 defines a guide channel. The guide channel wall 52 is bent over upon itself as at 54 and over the guide channel wall 47 of the guide channel 44 as shown in Figs. 3, 4 and 6.

The guide channel wall 54 which is bent over as described is extended forming a lip which is removably

frictionally received within the channel of the leg 40 of the Z-shaped member, as shown particularly in Figs. 3, 4, 6, 8, 9 and 10. The engagement of the lip portion of the folded over wall 54 within the channel of the leg 40 of the Z-shaped member 38 is what holds the sub-assembly upon the Z-shaped member.

Throughout the upper portion of the jamb assembly the screws 24 extend also through the leg 54 and serve to retain the parts together. Throughout the lower portions of the assembly the screws do not extend through the lip of the wall 54 and such lower portions of the sub-assembly are therefore readily removable, as shown in Fig. 7.

It will be seen that the sub-assembly which is made up of the guide channel 44 and the guide channel 48 is divided into upper and lower portions, as shown particularly in Figs. 6 and 7. The upper portions have a vertical dimension greater than the vertical dimension of the sash that are slidably mounted within the window assembly. The sash may therefore be elevated into the upper portion of the sub-assembly entirely clear of the lower portion and permitting removal, as shown in Fig. 7 by withdrawal of the lip 54 from the channel of the Z-shaped member.

In the window assembly the upper storm sash is indicated as U, the lower storm sash as L, and the screen as S. These sash structures are shown in position in Figs. 1 and 2 with the screen and one of the sash lowered in Fig. 2. In Fig. 5 all three sash are shown as elevated above the lower guide channel assembly and into the upper guide channel assembly. When it is desired to remove the sash from the assembly they are raised into the upper portions, as shown in Fig. 5. The lower portions of the guide channels which make up the sub-assembly may then be withdrawn, as shown in Fig. 7 because the lip 54 in the lower portion of the sub-assembly is of less width than the lip in the upper portion and is not pierced by the screws 24.

The side wall 46 of the channel 44 has its upper corner bent out of the plane of the channel, as shown at 58, in Figs. 5, 6 and 7 so that such yielding corner bend is disposed within the outer guide channel and therefore will serve to hold the sash U in the elevated position when the sash is raised thereabove, as shown in Fig. 5. Also as shown in Fig. 5, the side walls of the channels preferably present a wave-like contour as shown by reference character 60 so that friction is exerted upon the sash sliding through the channels sufficient to maintain them in positions of elevated adjustment.

It is apparent, therefore, that in a window frame as herein described not only will the sash be maintained at adjusted elevated positions but the sash may be relatively easily removed from the frame. Such sash may be raised into the upper portion of the window frame. The sub-assembly of each jamb assembly may then be withdrawn as shown in Fig. 7. Each sub-assembly may be withdrawn inwardly. Upon withdrawal of this sub-assembly a sash may be lowered from the upper half of the frame into the lower half. Such sash may then be moved laterally from the frame. Each of the sash may be thus removed.

For replacement the sash may be inserted into the lower half of the frame and elevated. Upon elevation of the sash the opposed assemblies may be reinserted and the window is ready for use. It does not require any tools or removal of screws or the like to effect the removal and replacement of the sash.

What I claim is:

1. A jamb assembly for a window structure having a frame provided with opposed complementary jamb assemblies, each jamb assembly having three adjacent parallel sash guide channels and comprising: a base channel, a generally Z-shaped member having one leg extending along one margin and projecting normal to the base of the Z-shaped member and folded upon itself

providing a lip receiving channel leg, said channel leg received within the base channel and grippingly engaged thereby, said Z-shaped member having its opposite leg projecting away from its opposite margin in the opposite direction from the first leg and providing one side wall for one of the three guide channels, a guide channel member U-shaped in cross section seated upon the base of the Z-shaped member having one side wall disposed spaced from the second mentioned leg of the Z-shaped member defining with said second mentioned leg of the Z-shaped member said one guide channel, a second guide channel member seated upon the bottom of the first guide channel member having one side wall spaced from a side wall of the first guide channel this side wall and the side wall of the U-shaped member defining therewith a second guide channel, said second guide channel member having its other side wall folded over upon itself and over a side wall of the first guide channel member and extending as a lip beyond the bottom of said first guide channel member and received within the lip receiving channel leg of the Z-shaped member and grippingly engaged thereby, said second guide channel member itself defining the third guide channel, and means for securing the jamb assembly to a supporting frame.

2. A jamb assembly for a window structure having upper and lower sliding sash and having a frame provided with opposed complementary jamb assemblies, each jamb assembly having three adjacent parallel sash guide channels, each jamb assembly comprising: a generally Z-shaped member having one leg projecting along one margin away from the base of the Z-shaped member and folded upon itself providing a lip receiving channel opening inwardly of the window opening and having its opposite second leg projecting along the opposite margin in the opposite direction from the first leg away from the base and disposed to provide a side wall for the third guide channel of the three guide channels, a guide channel sub-assembly seated upon the base of the Z-shaped member and having three parallel spaced side walls which define the first and second guide channels of said three guide channels, a side wall of the second guide channel being spaced from and parallel to said second leg of said Z-shaped member to define said third guide channel, said guide channel sub-assembly having a lip projecting in the opposite direction from its guide channel side walls and removably grippingly received within the lip receiving channel of the Z-shaped member, said Z-shaped member extending lengthwise throughout the jamb assembly, said guide channel assembly divided into upper and lower end portions, one of said end portions being removable from the base of the Z-shaped member independently of the other end portion by withdrawal of its lip from the lip receiving channel of the Z-shaped member.

3. A jamb assembly as defined in claim 2 characterized in that the lip of the upper portion of the guide channel sub-assembly received within the channel of the Z-shaped member is fastened therein against removal and the lip of the lower portion of the guide channel sub-assembly received within the channel of the Z-shaped member is frictionally held therein but is removable therefrom.

4. A jamb assembly for a window frame having opposed complementary jamb assemblies, each jamb assembly defining at least two side-by-side guide channels and comprising: a Z-shaped base member having one leg defining a side wall of one of said guide channels and having its other leg projecting away from the base of the Z-shaped member in the opposite direction from the first mentioned leg, said last mentioned leg folded upon itself defining a lip receiving channel the side walls of which are tensioned toward each other, a guide channel structure disposed upon the Z-shaped member with the bottom of its channel seated upon the base of the Z-shaped member and with the side walls of its channel projecting inwardly

of the window opening and defining a guide channel, one of said side walls spaced from the first mentioned leg of the Z-shaped member defining therewith another guide channel, said guide channel structure provided with a lip projecting away from the bottom of its channel in the opposite direction to the side walls of its channel, said lip removably received within the lip receiving channel of the Z-shaped member and grippingly engaged thereby.

5. A jamb assembly for a window frame as defined in claim 4 characterized in that the last mentioned leg of the Z-shaped member has its channel opening inwardly of the window opening and laterally offset the edge of the base of the Z-shaped member and the guide channel structure has its lip formed by a portion of one side wall of its guide channel folded over upon itself and projecting in the opposite direction away from the bottom of said guide channel.

6. A jamb assembly for a window frame as defined in claim 4 characterized in that the guide channel structure itself defines two side-by-side guide channels and the outer side wall of one of said guide channels is folded over upon itself and extends beyond the bottom of the channel in the opposite direction from the side wall and constitutes the lip received within the lip receiving channel of the Z-shaped member.

7. A jamb assembly for a window frame as defined in claim 4 characterized in that the guide channel structure comprises two channel members, one channel member being U-shaped in cross section and having its bottom seated upon the base of the Z-shaped member, the second channel member having its channel disposed within the channel of the U-shaped member and with its bottom seated upon the bottom of the U-shaped member, one of

the side walls of the second channel member being folded over a side wall of the U-shaped channel member and projecting beyond the bottom of the U-shaped channel member defining the lip of the guide channel structure.

8. A jamb assembly for a window frame as defined in claim 4 characterized in that the guide channel structure comprises two channel members, one channel member being U-shaped in cross section and having its bottom seated upon the base of the Z-shaped member, the second channel member having its channel disposed within the channel of the U-shaped member and with its bottom seated upon the bottom of the U-shaped member, one of the side walls of the second channel member being folded over a side wall of the U-shaped channel member and projecting beyond the bottom of the U-shaped channel member defining the lip of the guide channel structure and further characterized in that a channel-shaped base member is grippingly received over the lip receiving channel leg of the Z-shaped member and said channel base member is secured to a jamb part adjacent the window opening.
